Des. 197,821
Patented Mar. 24, 1964

197,821

HELICOPTER

Raymond L. Chaney, Palo Alto, and Edward H. Jacobsen,
Menlo Park, Calif., assignors, by mesne assignments, to
Eltra Corporation, Brooklyn, N.Y., a corporation of
New York

Filed Mar. 30, 1962, Ser. No. 69,504

Term of patent 14 years

(Cl. D71—1)

Fig. 1

Fig. 2

Fig. 5

Fig. 6

Fig. 7

FIGURE 1 is a perspective view of the front and starboard side of a helicopter embodying our new design;

FIGURE 2 is a perspective view of the rear and port side of the helicopter;

FIGURE 3 is a top plan view thereof;

FIGURE 4 is an elevational view of the starboard side thereof; and

FIGURES 5, 6 and 7 are broken, fragmentary sectional views respectively taken along the lines 5—5, 6—6 and 7—7 of FIGURE 1.

The dominant features of our design reside in the portions shown in full lines.

What is claimed is:

The ornamental design for a helicopter, substantially as shown and described.
